GAS BURNER FOR WATER HEATERS OR THE LIKE

Robert J. Ditto, Chattanooga, Tenn., assignor to W. L. Jackson Manufacturing Company, Inc., Chattanooga, Tenn., a corporation of Tennessee

Application March 10, 1958, Serial No. 49,982

Term of patent 14 years

(Cl. D81—10)

FIG. 1

FIG. 4

FIG. 2

FIG. 3

Fig. 1 is a top plan view of a gas burner showing my new design;

Fig. 2 is a front elevation of the same;

Fig. 3 is a side elevation of the same; and

Fig. 4 is a perspective view of the same.

I claim:

The ornamental design for a gas burner for water heaters, or the like, substantially as shown.
